FIG. 1 is a top plan view of a boat hull showing the new design.

FIG. 2 is a side elevational view of the boat shown in FIGS. 1 and 2.

FIG. 3 is a bottom plan view of the boat shown in FIGS. 1 and 2.

FIG. 4 is a front elevational view of the boat shown in FIGS. 1 and 2.

FIG. 5 is a rear elevational view of the boat shown in FIGS. 1 and 2.

FIG. 6 is a perspective view of the boat shown in FIGS. 1, 2 and 3.

FIG. 7 is a sectional profile view taken along line 7-7 of FIG. 2.

FIG. 8 is a sectional profile view taken along line 8-8 of FIG. 2.

FIG. 9 is a sectional profile view taken along line 9-9 of FIG. 2.

The dominant features of my design reside in the portions shown in full lines. The deck, windshield and cockpit areas shown in broken lines have been omitted from FIGS. 5 and 6 for clarity of illustration.

I claim:

The ornamental design for a boat hull, as shown and described.
